CLAIM

The ornamental design for a combined backpack and cooler, as shown and described.

DESCRIPTION

FIG. 1 is a perspective view of combined backpack and cooler showing my new design;

FIG. 2 is a right side elevational thereof;

FIG. 3 is a top plan view thereof;

FIG. 4 is a bottom plan view thereof, the shoulder straps and carrying loop being removed for clarity of illustration;

FIG. 5 is a front elevation thereof; and,

FIG. 6 is a rear elevation thereof.

The broken lines shown in FIGS. 1, 2, 3, 5, and 6 are understood to represent conventional stitching.

FIG. 1

FIG. 2

FIG. 3

FIG. 4

FIG. 5

FIG. 6
